FLUID PRESSURE ENERGY TRANSLATING
DEVICEThomas E. Raymond, Zanesville, Ohio, assignor
to Simplex Engineering Company, Zanesville,
Ohio

Application August 9, 1946, Serial No. 689,548

14 Claims. (Cl. 103—182)

1

This invention relates to fluid pressure energy translating apparatus and is particularly directed to an improved hydraulic pump or motor for use in circuits employing high fluid pressure. This application is a continuation in part of my co-pending application Serial No. 529,957, filed April 7, 1944, now abandoned.

An object of this invention is to provide a pump or motor having a plurality of radially arranged cylinders in which pistons are disposed for movement, and a centrally located actuating or operating member with which the pistons directly engage, the pistons serving either to cause fluid to flow from a reservoir or storage place to a hydraulic system for use therein or to transmit motion to the centrally arranged member when the device is employed as a motor.

Another object of this invention is to provide a pump having a body with a central chamber, and a plurality of cylinders radiating therefrom, the pistons being disposed for movement in the cylinders to withdraw fluid from the central chamber and force it under pressure into a hydraulic system, the flow of fluid into the central chamber and through the cylinders serving to keep the moving parts of the apparatus well lubricated at all times.

A further object of this invention is to provide a pump having a circular body with a central chamber and radiating sockets which open to the exterior of the body to receive cylinder sleeve and piston assemblies which can be individually removed, repaired and replaced without further dismantling the pump.

A still further object consists in providing a pump having a casing with a central chamber and a plurality of cylinders radiating from the chamber and receiving pistons, an eccentric for cooperation with the pistons being carried by a shaft which is journaled in the casing and has a portion projecting from the casing through a hollow boss formed with the casing, the shaft being formed for connection with a driving member, the hollow boss receiving a mounting sleeve which serves to connect the pump casing to a support and hold the pump shaft in proper alignment with the driving member, thus eliminating strain and incidental coupling noises.

It is also an object to provide a novel piston and cylinder sleeve assembly wherein the piston is formed with a passage having a valve seat for engagement by a valve when the piston is moved in a direction to force fluid out of the cylinder and away from the seat when the piston is moved in the opposite direction, the piston having an

2

expansible skirt to sealingly engage the cylinder walls and prevent the escape of fluid around the piston during the pumping strokes.

An object of the invention also consists in providing a piston with a hollow interior which is shaped to form a thin expansible skirt wall, a valve chamber separated from the thin skirt portion by an internal shoulder and passage means extending from the valve chamber to one end of the piston, a ball valve being disposed in the valve chamber to control the direction of fluid flow through the piston and a perforated abutment being engaged with the internal shoulder to limit the movement of the ball valve away from its seat and thus increase the speed of operation of the valve.

Further objects and advantages of the present invention will be apparent from the following description, reference being had to the accompanying drawings wherein a preferred form of embodiment of the invention is clearly shown.

In the drawings:

Fig. 1 is a vertical longitudinal sectional view taken through a hydraulic pump formed in accordance with the present invention showing the same operatively connected with a driving unit;

Fig. 2 is a vertical transverse sectional view taken on the plane indicated by the line 2—2 of Fig. 1; and

Fig. 3 is a detail horizontal sectional view taken on the plane indicated by the line 3—3 of Fig. 2.

In the embodiment of the invention illustrated in the drawings, the pump comprises a circular casing 20 having a body 21 and inner and outer end caps 22 and 23. The caps 22 and 23 are secured to the body by screws 24 to complete the casing 20. The body 21 is provided at one end with an axially disposed recess 25 into which is inserted (by pressing, shrinking or otherwise) a spool-like member 26 which forms a bearing holder. Between its ends, the member 26 is relieved on the outer side to provide an annular groove which cooperates with the inner wall of the recess 25 to form an inlet manifold 27. The length of the member 26 is such that when it occupies its innermost position in the recess 25, the outer portion of the recess will serve as a chamber 28, closed at its end by the inner end cap 22. The latter cap also has a recess 29 substantially conforming in diameter to the inner diameter of the member 26. Races 31 of needle bearings 32 and 33 are disposed in the recess 29 and member 26 and these races contain rollers 34 which receive and rotatably support the main

shaft 35 of the pump.

The end cap 22 has a longitudinally extending bore 36 which reaches from the recess 29 to the outer end of a boss 37 forming an extension of the cap 22. This boss has its outer end counter-bored, as at 38, for the reception of packing rings 39 employed to seal the space between the shaft and the inner wall of the boss 31. These sealing rings prevent the escape of hydraulic fluid from the chamber 28 when the pump is connected in a hydraulic circuit.

Oil is preferably used for the hydraulic fluid and is supplied to the manifold 27 through an inlet pipe 41 which has a threaded connection 42 with the body 21. The pipe 41 communicates with an inlet port 43 formed in the body 21 and communicating in turn with the inlet manifold 27. The formation of the member 26 provides a wall 44 between the manifold 27 and the chamber 28, which wall 44 is provided at circumferentially spaced intervals with ports 45 to establish communication between the manifold 27 and the chamber 28. These ports 45 are of sufficient size and number to provide an ample flow of hydraulic fluid into the chamber 28 for pump operation.

Body 21 is also provided with a plurality of radially extending recesses 46 which lead from the chamber 28 to the exterior of the body 21. The outer end portions of these recesses are threaded at 47 to receive threaded enlargements 48 of cylinder sleeves 49. The inner portions of the recesses 46 are reamed to an accurate size while the portions of the cylinder sleeves 49 positioned therein may be formed with a slight taper terminating immediately below the threaded portion in a diameter at least one thousandth of an inch greater than that of the reamed portions of the recesses. This construction provides a secure seal against fluid leakage around the sleeves. It also serves to compress the sleeves to a limited extent, to secure a better seal between the pistons 50 disposed for sliding movement in the sleeves 49, and the inner walls of the sleeves. To prevent this compression of the sleeves from binding the pistons, the inner surfaces of the sleeves are ground while the sleeves are held in a fixture (not shown) under the same conditions which are imposed when the sleeves are mounted in the body 21. In actual practice, it has been found that substantially the same results can be obtained without tapering the sleeve. Preferably the inner surfaces of the recesses 46 are ground and lapped and the outer surfaces of the sleeves 49 are treated in like manner so that the sleeves 49 fit snugly within the recesses. This is known in the trade as "ring fitting." When extreme accuracy is desirable, it can be reduced to zero by selecting sleeves that accurately fit the recesses.

The outer ends of the cylinder sleeves have heads 52 which, in the present instance, are formed with wrench receiving sockets 53 to facilitate threading the cylinder sleeves into the body 21. Each of the cylinder sleeves is provided with a washer 54 for engagement with a seat 55 formed around the outer end of each socket 47. These washers seal the joints between the cylinder sleeves and the body 21 and effectively prevent the escape of hydraulic fluid at these locations.

A channellike ornamental ring 56 surrounds the body 21 and the heads 52 of the cylinder sleeves and serves to protect the heads 52 from injury when the pump is in use. The outer wall of this ring is provided with openings 57 through

which the cylinder sleeves may be inserted and withdrawn.

As mentioned above, the inner portions of the cylinder sleeves are accurately ground and lapped inside to receive, for sliding movement, the hollow piston members 50. The outer surfaces of the pistons are also ground and lapped. The piston members and the cylinder sleeves form an assembly which may be withdrawn and reinserted without otherwise dismantling the pump. A coil spring 60 is arranged between the inner end wall 61 of each cylinder sleeve and a perforated abutment plate 62 disposed in the piston 50 against a shoulder 63 formed therein, the coil spring 60 tending to urge the piston out of the sleeve and into the chamber 28. The portion of the piston wall surrounding the spring 60 is made thin and expansible so that on the working strokes of the piston, the thin skirt-like wall will expand and closely engage the inner surface of the cylinder sleeve thus sealing this junction against fluid flow. On the return stroke the pistons, not being under any expanding pressure, will return to normal size and slide freely in the sleeves under the influence of the springs 60.

Preferably the pistons are formed of different steel than the sleeves and are heat treated to different hardness than the sleeves for the purpose of minimizing wear and adhesion between the pistons and sleeves. Either the steel of pistons or the steel of sleeves may contain graphite, and in the preferred embodiment, the steel of the pistons contain the graphite.

The sleeves 49 are formed of steel bar stock of S. A. E. specification No. 4145, heat treated to 30 C. Rockwell after machining. In one embodiment of the apparatus, the exterior of the sleeve 49 is ground to a microfinish of 15 R. M. S., the diameter being .7505 inch with tolerance of +.0000 and -.0002 inch. The interior of the sleeve is reamed to .625 inch and honed to .627 inch. The inner surfaces of the sleeves are finished to a microfinish of 10 R.M.S. after honing and held to a tolerance of +.0005 and -.0000 inch. The pistons are formed of the suitable die steel which preferably contains some graphite, and one of the steels that work highly satisfactorily is manufactured by Timken Steel and Tube Division of the Timken Roller Bearing Company of Canton, Ohio, which steel is sold under the trade name of "Graph-Mo." This steel is heat treated to 59 to 61 C. Rockwell and the exterior is microfinished to 10 R. M. S. after honing and held to a tolerance of +.0005 and -.0000 inch. The surfaces of the pistons are ground to an outside diameter of .627 inch and honed to an outside diameter of .625 inch. This finished diameter is maintained to tolerances of +.001 and -.000. The inside diameter of outer skirt portion of the pistons is .5312 inch and this dimension is held to the tolerance of .005 inch.

Obviously, the tolerances between the outer diameter of the pistons and the inner diameter of the sleeves can be minimized by selecting pistons which have the desired tolerance with respect to the inner diameter of the sleeves.

Obviously the outer skirt portion of the piston can be varied somewhat, particularly when the pistons are made of smaller or larger diameters, however, it is important to provide for the expansion of the skirt during the working stroke of the piston, and it is also important to limit the degree of expansion of the piston to well within the elastic limit of the steel since it is highly desirable that the pistons contract in the cycle of

reciprocation to permit the ingress of lubricating oil upon each inward stroke of the piston. The time period, at which the piston is expanded to its extreme limit is of such short duration that with the minimum amount of oil present at the time, no galling takes place.

Below the shoulder 63, each piston 50 is provided with a valve chamber 64 for the reception of a ball valve 65 which engages a seat 66 at the inner end of the valve chamber 64. The seat 66 and the shoulder 63 are so spaced that the valve 65 will be limited in its movement away from the seat to the extent necessary to provide sufficient flow through the piston. Thus in switching from the intake to the compression strokes of the piston, there will be no appreciable time lag in the closing of the valve and the efficiency of the pump will be high. Passages 67 and 68 establish communication between the interior of the piston and the chamber 28. The former, passages 67, extend transversely of the piston and terminate in ports in the side walls of the piston. A port 69 is also formed in the inner end of the piston 50, this port registering with an annular groove 70 provided in the outer surface of an anti-friction bearing 71.

The bearing 71 is carried by an eccentric enlargement 72 formed on the shaft 35 within the chamber 28. This bearing 71 eliminates the friction which in the absence of the bearing, would result when the eccentric moved from one side of the longitudinal axis of a piston to the other during the rotation of the eccentric, thereby prolonging the life of the pump. The elimination of friction at this point also assists in reducing the power required to operate the pump.

As illustrated in Figs. 1 and 2, the sockets or recesses 47 are enlarged circumferentially, as at 73, at the inner ends of the threaded portions 48 and when the cylinder sleeves are inserted in the body, these enlargements of the recesses cooperate with the cylinder sleeves to form chambers 74 which communicate with the interior of the cylinder sleeves through outwardly extending channels 75 formed in the threaded exterior portions of the cylinder sleeves and through ports 76 extending through the side walls of the sleeves. Each chamber 74 communicates with a longitudinally extending passage 77 formed in the body 21, which passage communicates with an angularly extending passage 78, the latter terminating in an exhaust or outlet manifold 79 formed in the outer end face 80 of the body 21. This manifold chamber is closed by the end cap 23, an outlet port 81 being formed centrally of this cap to permit the flow of hydraulic fluid from the outlet manifold. A pipe 82 is threaded into the outlet port 81 to conduct fluid from the pump to the hydraulic system.

The passages 77 are formed by drilling holes 83 into the body 21 from the outer end face 80. These holes 83 are reduced in diameter between their points of connection with the angular passages 78 and the chambers 74 to provide valve seats 84 for engagement by ball valves 85 disposed in the holes 83. These valves are urged into engagement with the seats by coil springs 86, one end of each spring engaging a ball valve 85 and the other end engaging a shoulder 87 formed on a valve stop 88. The member 88 has a reduced extension 90 which projects through the spring 86 and terminates in spaced relation from the valve 85, to permit limited opening movement of the valve. Members 88

are retained in the body 21 through threaded engagement therewith, each member 88 having a head 91 formed with a wrench socket (not shown). The head 91 engages a washer 92 to prevent the escape of fluid around the threaded portion of the stop member. A washer 93 is also positioned between the end cap 23 and the body 21 to prevent the escape of high pressure fluid at the joint therebetween.

10 The pump 20 is connected for operation by positioning a mounting sleeve 94 on the boss 37 and connecting the outer end of this mounting sleeve with a support 95 for a driving member 96, this member being splined as at 97 to the shaft 35. In the present instance, the member 96 constitutes the armature shaft of a driving motor and the support 95 constitutes the motor casing. The sleeve 94 is preferably split at one side and is clampingly secured to the casing 95 and boss 37 by drawing the spaced portions of the sleeve together with clamping screws 98. A third screw 99 is provided to spread the spaced portions apart when it is desired to remove the sleeve. This method of mounting insures the accurate registration of the pump shaft 35 with the shaft 96 of the driving motor, the latter having a socket in its outer end to receive the end of the shaft 35. If desired, the end of shaft 96 can be formed with a socket to receive a nut which in turn has a splined connection with the pump shaft 35.

20 As shown in Fig. 1, the inner end wall of the armature shaft 96 is provided with a reduced socket 101 to receive a small compression spring 102. One end of this spring engages the end 35 of the pump shaft 35 and tends to urge it outwardly of the socket. This force causes the opposite end of the motor shaft to engage a bearing disk 103, inserted in the body 21 at the end of the recess 25 and thus preclude longitudinal 40 movement of the shaft during use of the pump.

30 To facilitate the removal of the disk 103 and the bearing 33, the casing 21 has a plurality of openings 104 through which a suitable tool can be passed to force out these members. In normal use, the openings 104 are closed by plug screws 105.

40 The operation of the pump is as follows: Current is introduced to the driving motor to cause the shaft 96 to revolve. This shaft in turn imparts revolving motion to the shaft 35 and the eccentric 72 forming a part thereof. As this eccentric revolves, pistons 50 are reciprocated in the cylinder sleeves 49. The springs 60 urge the heads of the pistons into engagement with the bearing 71 carried by the eccentric and when the low side of the eccentric approaches each piston, the piston is moved into chamber 28 by its spring 60. During this motion, fluid will flow from the chamber 28 through the passages 67, and 68, past the valve 65 through valve chamber 64 and the openings in plate 62 into the spring chamber of the piston. Since the valve 65 merely rests on its seat 66, the movement of the piston into the fluid in the chamber 28 will be sufficient to permit the fluid to raise the valve from its seat and flow into the cylinder sleeve. When the high side of the eccentric approaches each piston and moves it outwardly, the valve will engage its seat, trapping the fluid in the piston and cylinder sleeve. Continued outward movement of the piston will force the fluid out through ports 76 and channels 75 to passages 77 and 78 to the outlet manifold 79. Reverse flow of this fluid is prevented by the valve 85 engaging seat 84. Thus, when a particular piston moves into the chamber 28 on the following

stroke, a fresh charge of fluid will be supplied to the cylinder sleeve.

By conducting the fluid from the inlet port through the chamber 28 and through the pistons into the cylinder sleeves, all the moving parts of the pump will be constantly lubricated. Some advantages resulting from the removable piston and cylinder sleeves have previously been mentioned. Another advantage flowing from this construction is the ability to quickly change from one fluid pressure capacity to another by merely exchanging the pistons and cylinders in the pump for others having the required diameters. When a high fluid pressure is to be developed, the piston and cylinder diameter is decreased in order to preserve safe bearing loads.

While the form of embodiment of the present invention as herein disclosed constitutes a preferred form, it is to be understood that other forms might be adopted, all coming within the scope of the claims which follow:

1. A hydraulic pump comprising a casing having a chamber and a plurality of recesses radiating therefrom, said recesses opening at their outer ends to the exterior of said casing, said casing having inlet and outlet passages communicating with the chamber and recesses respectively; actuating means in said chamber; piston and cylinder assemblies removably disposed in each recess, each of said assemblies having a cylinder sleeve inserted in a recess in said casing and a piston being formed of metal and slidably disposed in said sleeve, said piston having a longitudinally extending passage; and valve means in said passage to prevent fluid flow from the interior of said sleeve to the chamber in said casing.

2. A hydraulic pump comprising a casing having a chamber and a plurality of recesses radiating therefrom, said recesses opening at their outer ends to the exterior of said casing, said casing having inlet and outlet passages communicating with the chamber and recesses respectively; actuating means in said chamber; piston and cylinder assemblies removably disposed in each recess, each of said assemblies having a cylinder sleeve inserted in a recess in said casing and a piston being formed of metal and slidably disposed in said sleeve, said piston having an internal chamber connected by a passage with the chamber in said casing; valve means to control fluid flow from the piston chamber to the chamber in said casing; and resilient means in said piston chamber tending to move said piston from said cylinder sleeve into said casing chamber.

3. A hydraulic pump comprising a casing having a chamber and a plurality of recesses radiating therefrom, said recesses opening at their outer ends to the exterior of said casing, said casing having inlet and outlet passages communicating with the chamber and recesses respectively; actuating means in said chamber; piston and cylinder assemblies removably disposed in each recess, each of said assemblies having a cylinder sleeve inserted in a recess in said casing and a piston being formed of metal and slidably disposed in said sleeve, said piston having a skirt portion at the outer end of such thickness so as to expand radially under pressure within the skirt for sealing engagement with the inner wall of said cylinder sleeve; a passage extending from the inner to the outer end of said piston; valve means controlling fluid flow through said passage; and means between said piston and cylinder sleeve tending to move said piston out of said cylinder sleeve.

4. A hydraulic pump comprising a casing hav-

ing a chamber and a plurality of recesses radiating therefrom, said recesses opening at their outer ends to the exterior of said casing, said casing having inlet and outlet passages communicating with the chamber and recesses respectively; actuating means in said chamber; piston and cylinder assemblies removably disposed in each recess, each of said assemblies having a cylinder sleeve inserted in a recess in said casing and a piston being formed of metal and slidably disposed in said sleeve, said piston having a spring chamber and a valve chamber; a shoulder between said chambers; a perforated plate engaging said shoulder and serving as a spring abutment; a spring engaging said abutment and said cylinder sleeve; a passage connecting said valve chamber and the chamber in said casing; and valve means in said valve chamber to prevent reverse fluid flow through said passage, said perforated plate serving to limit the movement of said valve means in said valve chamber.

5. A fluid pressure energy translating device comprising a housing having a chamber with a plurality of recesses radiating therefrom and inlet and outlet passages communicating with the chamber and recesses respectively; a cylinder sleeve removably positioned in each recess, the interiors of said sleeves being in communication with said passages; valve means in said outlet passages to prevent reverse flow of fluid therethrough; a shaft journaled in said housing, said shaft having an eccentric portion in said chamber; a metallic piston disposed for longitudinal movement in each cylinder sleeve; means urging said pistons toward said eccentric, rotation of said eccentric serving to move said pistons in opposition to said urging means, said pistons having passages extending therethrough; and valve means in said piston passages to prevent fluid flow from said cylinder sleeves to said chamber.

6. A hydraulic pump comprising a housing having a chamber with a plurality of recesses radiating therefrom and inlet and outlet passages communicating with the chamber and recesses respectively; a cylinder sleeve removably disposed in each recess, said sleeves having their interiors in communication with said outlet passages; metallic pistons disposed for longitudinal movement in said cylinder sleeves; means between said cylinder sleeves and pistons tending to urge the latter elements toward said chamber; means in said chamber for successively moving said pistons in opposition to said urging means; and valved passages connecting said chamber and the interior of said cylinder sleeves at the outer ends of said pistons.

7. A hydraulic pump comprising a casing having a chamber and a plurality of recesses radiating therefrom; said casing having inlet and outlet passages communicating with the chamber and recesses respectively, the recesses opening at the outer ends to the exterior of said casing; a cylinder sleeve removably positioned in each recess; a metallic piston disposed for longitudinal movement in each cylinder sleeve; and means in the chamber in said casing for imparting movement to said pistons.

8. In a fluid pressure energy translating device, a piston and cylinder sleeve assembly comprising, in combination, a sleeve-like body having one end closed, the wall of said body being provided with port means at the closed end; a metallic piston disposed for sliding movement in said body, said piston being open at the end within said body and having a passage extending to the opposite

end; valve means in said passage to control the fluid flow through said passage; and means between said piston and said body tending to urge the former out of the latter.

9. In a fluid pressure energy translating device, a piston and cylinder sleeve assembly comprising, in combination, a sleeve-like body having one end closed, the wall of said body being provided with port means at the closed end; metallic piston means disposed for sliding movement in said body, said piston means having a skirt portion within said body, said skirt portion being of such thickness so as to expand radially under pressure within the skirt, said piston forming a passage extending from the inner to the outer end; and valve means for controlling fluid flow through said passage.

10. In a fluid pressure energy translating device, a piston and cylinder sleeve assembly comprising, in combination, a sleeve-like body having one end closed, the wall of said body being provided with port means at the closed end; a hollow metallic piston disposed for sliding movement in said body, said piston being open at the end within said body; a perforated abutment plate dividing the interior of said piston into spring and valve chambers; said piston forming a passage establishing communication between said valve chamber and the outer end of said piston; valve means in said valve chamber to control fluid flow through said passage, said abutment plate limiting the movement of said valve means; and spring means between the closed end of said sleeve and said abutment plate, said spring tending to urge said piston out of said sleeve.

11. In a fluid pressure energy translating device, in combination, a cylinder; a piston within the cylinder, said piston having a diameter normally less than the diameter of the interior of the cylinder, said piston having a head and a resilient metallic skirt, said skirt being of such thickness so as to expand radially under pressure within the skirt, the characteristics of the metal skirt being such that the skirt contracts to normal diameter when the pressure is removed; and movable means operatively associated with the head of the piston.

12. In a fluid pressure energy translating device, in combination, a metallic cylinder; a piston within the cylinder, said piston having a diameter normally less than the diameter of the interior of the cylinder, said piston having a head and a resilient metallic skirt, said skirt being of such thickness so as to expand radially under pressure within the skirt, the characteristics of the

metal skirt being such that the skirt contracts to normal diameter when the pressure is removed, one of said metals containing graphite; and movable means operatively associated with the head of the piston.

13. In a fluid pressure energy translating device, in combination, a hardened metallic cylinder; a piston within the cylinder, said piston having a diameter normally less than the diameter of the interior of the cylinder, said piston having a head and a resilient hardened metallic skirt, said skirt being of such thickness so as to expand radially under pressure within the skirt, the characteristics of the metal skirt being such that the skirt contracts to normal diameter when the pressure is removed, one of said metals having a different hardness than the other; and movable means operatively associated with the head of the piston.

14. In a fluid pressure energy translating device, in combination, a hardened metallic cylinder; a piston within the cylinder, said piston having a diameter normally less than the diameter of the interior of the cylinder, said piston having a head and a resilient hardened metallic skirt, said skirt being of such thickness so as to expand radially under pressure within the skirt, the characteristics of the metal skirt being such that the skirt contracts to normal diameter when the pressure is removed, one of said metals containing graphite and one of said metals having a different hardness than the other; and movable means operatively associated with the head of the piston.
